UNITED STATES PATENT OFFICE.

HARRY BARLOW, OF PORT MADISON, WASHINGTON, ASSIGNOR TO BARLOW MARINE ELEVATOR CO. INC., OF SEATTLE, WASHINGTON, A CORPORATION OF WASHINGTON.

MARINE ELEVATOR.

Application filed January 24, 1927. Serial No. 163,290.

My invention relates to a marine elevator. More particularly my invention relates to means for causing an elevator platform supported at its four corners to be moved transversely of its flight towards the deck of a moored vessel to bridge the gap which ordinarily obtains between said vessel and the face of the dock.

For purposes of clearness and definiteness of illustration, I will describe a marine application of my invention under conditions obtaining on a dock to which a vessel may be moored for purposes of loading and unloading, but it will be expressly understood that my invention is not to be limited to any such specific application but extends to all mechanisms operating under similar conditions.

My invention is directed particularly to solving the problem of loading and unloading vessels where tidal variation obtains. The term "tidal variation" herein includes both the difference in level of fresh water in rivers or lakes where spring freshets and the summer droughts cause great variation in the levels of the water, as well as where variation is due to true tidal action occurring in the oceans.

There are the following situations:

(1) Where the deck of the vessel from or to which the freight is to be moved is above the level of the dock and there is a considerable gap between said deck and the edge of the elevator platform which is to be spanned, a simple and common expedient is to fix in place on the deck of a vessel a transfer board which extends over said gap, the elevator working up to the under edge of said transfer board.

(2) When the deck of the vessel from or to which the freight is to be moved is below the level of the dock then the elevator may be of such construction that the platform may be capable of being moved outwardly, or

(3) The platform itself may be provided with means herein called an "apron", which may be extended to bridge the gap when the platform is on a level with the deck of the vessel, and which means may be retracted to clear the upper deck of the vessel as the elevator platform travels to the level of the dock. The present invention relates to the situation where the platform itself is moved bodily outwardly to bridge the said gap. It will be understood that in moving freight to

and from a vessel, it is always done with the utmost speed in order not to delay the vessel any longer than necessary, since all time when said vessel is not under way is considered loss.

A special difficulty obtains in providing elevator mechanism for docks in that the mechanism must be such as to permit the dock being swayed or sprung out of its normal position by contacting the vessel without interfering with the operation of the elevator. The moving parts must be such as to not become bound or thrown out of alignment to an extent that will interfere with their operation.

In providing for a throwout means for the platform provision must be made for the further following operating conditions: The throwout must be possible at any desired level intermediate the flight of the elevator platform. Also the commencement of the throwout movement must be smooth, i. e., free of jar and must not interfere with the speed with which the elevator may be raised and lowered. Moreover, the throwout means must be so provided as not to interfere with its swinging freely within the elevator well. In short, the provision for the adjustable throwout means must be such as to provide for causing the platform and the throwout means to contact in such a manner as to avoid all jar and at the same time not interfere with the platform's freedom of movement. Manifestly if there is a jarring upon each rise and fall of the elevator upon contacting said throwout means, the same would be objectionable not only on account of the wrecking and wearing of the elevator mechanism but there is the objection on account of freight produced on the part of the passengers on the elevator platform, also where automobiles are being transferred such jolting might result in dislodging the same, and also objection obtains on account of the loss of freight which may be thrown therefrom, or if not thrown from the platform it might be thrown upon the platform from a hand truck upon which the goods may be stacked, such as crates of eggs and other freight of like fragile character.

Ofttimes it is desirable that the elevator platform and an associated superstructure mounted on the dock deck adjacent to the well should provide a clear open space so that the freight may be trucked laterally of

the elevator platform to the dock. Furthermore, such a clearance on the dock deck is often required by fire ordinance so that a fire apparatus may not be hindered in its movement over the dock deck. Such conditions require special construction of the throwout mechanism so that the superstructure incident thereto is eliminated or reduced to an unobjectionable degree.

10 A further operating condition to be con-
sidered in providing the throwout mecha-
nism is the matter of different running
speeds of the elevator platform which obtain
in different installations; i. e., in one installa-
15 tion the distance of travel of the elevator
may be ten feet while in other installations
the tidal variation (particularly river con-
struction) may require an installation of
thirty or more feet. In the latter case the
20 running speed of the elevator platform is
about twice that of the former. However,
the throwout mechanism is preferably
(among other reasons that of standardiza-
25 tion) identical in construction in both cases
and must be such as to be equally operable in
both instances.

A primary object of my invention is to provide an elevator platform with associated throwout mechanism which will satisfy each and all these conditions and requirements.

The above general objects of my invention, together with others inherent in the same, are obtained by the device illustrated in the following drawings, the same being preferred exemplary forms of embodiment of my invention throughout which drawings like reference numerals indicate like parts.

Figure 1 is a view in side elevation of a marine elevator embodying my invention.

40 Fig. 2 is an enlarged view in side elevation of a throwout member adjustable to different levels.

45 Fig. 3 is a plan view of said adjustable throwout member and a portion of the elevator platform.

A marine elevator platform 4 is operatively suspended by hoisting cables 5 disposed at each of the four corners of the platform. The said cables are secured to drum 6 and independent cable 7 is also secured to drum 6, and to this latter cable elevator counterweight 8 is secured. Motor means 9 actuates drum 6.

55 A roller 10 is operatively mounted on the end of shaft 11 which shaft is carried on the under side of the platform 4, the said rollers being disposed on each side of the rear end of the platform.

The said rollers 10 engage throwout guide members which are slidably mounted on each side of the elevator well as follows: An angle guide, or trackway, 12 is secured by angle clips 13 to dock beams 14 carried by the dock piling 15. I beam guides or trackways, 16 are secured by the angle clips 17 to dock

beams 14. Between and against these two trackways or guides 12 and 16 which are disposed on each side of the elevator well throughout members are slidably disposed.

These throwout members may be formed as follows: A bottom angle iron 18 is provided with a slot 19 to engage trackway 12 (see Fig. 2 and Fig. 3). A vertical angle iron 20 is secured by angle clip 21 to the bottom angle member 18. To angle irons 18 and 20 an angle iron 22 preferably curved is riveted having the flange member at the upper end extend across the rear side of the I beam. To this upper end flange portion of angle iron 22 may be secured block 23 which is slidably disposed against the I beam 16. On the opposite side a block 24 may be secured to the angle iron 20, and this block in turn is slidably disposed against I beam 16. Similar blocks (not shown) are also disposed at the lower end of angle iron 20. The flange member 25 of angle iron 22 provides a curved pathway to be engaged by the roller 10 mounted on the elevator platform. The angle clip bumper 26 having a rubber block 27 is secured to the upper end of angle iron 20. This bumper provides for the throwout member to be engaged by the edge portion of the platform and carried upwardly with it so that the throwout member may travel with the elevator platform for a part of its flight.

A cable 28 secured to the dock deck on drum 29 extends over sheave 30 for each throwout means and thence through an opening in a clip secured to the back side of angle iron 18, and is made fast to a bumper block 32 having the spring 33. This provides a support to limit the descent of the throwout guide member. A fixed but hingedly mounted apron 34 may be mounted on the end of the elevator platform.

The mode of operation of the marine elevator embodying my invention is as follows:

Assuming that the vessel is moored against the dock and that the side port opening is opposite the position shown by the platform in dotted line, the cable 28 is payed out from drum 29 until said bumper block is on a level with the deck of the vessel, i. e. in the position indicated in Fig. 1. The drum 29 which may be of the worm gear type is self-locking. The platform 4 which carries with it the throwout members on each side thereof by means of the angle clip bumpers 26 is lowered. In its descent, the throwout members slide down their fixed guide or track ways 12 and 16 and likewise each slides down the cable 28 until the bumper block 32 is contacted. Thereupon, the descent of the throwout members is arrested and is maintained at the level of the bumper. Then as the platform 4 descends roller 10 directly engages the curved trackway 25 and the platform is manifestly forced endwise, i. e. in a direction at right

angles to the vertical, towards the vessel to an extent necessary to permit the spanning of the gap between the deck of the vessel and the dock. Then, when the freight loaded 5 trucks are loaded upon and occupy all available room on the elevator, the same may be elevated and as it rises it is manifest that the platform edge will swing inwardly as its rollers 10 run up the trackway 25, and engage 10 the bumper 26 and carry the throwout means upward with the platform. The elevator is hoisted until it reaches the level of the deck 35 of the dock or to such other height as may be desired, such as to the height of a truck 15 which may be backed up to the elevator well so that the freight may be run directly off the platform on to the floor of the truck, or the elevator may be elevated to any other level, as another story, at which it is desired to 20 move the freight.

When the freight is removed, the elevator platform is again lowered to the level of the deck of the vessel. It will be noted that since the throwout means member is carried by the 25 platform 4 it does not cause a sudden jar or jolt when the throwout means contacts with the bumper block 32, and the roller 10 engages the trackway 25 since direct contact is maintained between the two at all times. 30 The throwout motion starts without any objectionable jarring or bumping. The hoisting cables 5 at the forward or water edge of the platform are preferably backwardly inclined in order to maintain the roller 10 of the 35 elevator platform against the I beam guide 16 and the track guide 25 of the throwout member.

The elimination of sudden jolts and jars is fundamentally important for the reasons 40 hereinbefore stated.

The construction of this throwout means and its mounting and method of engaging the elevator platform 4 provides for overcoming any swaying or displacement of the 45 dock by reason of the vessel being moored against the same. Manifestly, in place of roller means 10 a sliding shoe or other contacting means could be substituted for said roller.

50 Obviously changes may be made in the forms, dimensions and arrangement of the parts of my invention, without departing from the principle thereof, the above setting forth only a preferred form of embodiment.

55 I claim:

1. A marine elevator embodying an elevator platform suspended at its four corners having a roller means operatively mounted on each side thereof; and adjustable throwout 60 guide members operatively mounted with respect to said rollers whereby said platform

may be moved in a direction at right angles to the vertical at any desired point intermediate its flight.

2. A marine elevator embodying an elevator platform suspended at its four corners having a roller means operatively mounted at each side thereof; adjustable throwout guide members operatively mounted with respect to said rollers whereby said platform may be 65 moved in a direction at right angles to the vertical at any desired point intermediate its flight; and fixed guides for each of said guide members. 70

3. A marine elevator embodying an elevator platform suspended at its four corners having a roller means operatively mounted at each side thereof; throwout guide members operatively mounted with respect to said rollers whereby said platform may be moved in a 75 direction at right angles to the vertical at any desired point intermediate its flight; fixed guides for each of said guide members; and an adjustable supporting means upon which each of said guide members is slidably mounted 80 embodying a drum, a cable suspended from said drum, and a bumper block secured to one end of said cable. 85

4. A marine elevator embodying an elevator platform suspended at its four corners having a roller means operatively mounted on each side thereof; throwout guide members operatively mounted with respect to said rollers whereby said platform may be moved in a direction at right angles to the vertical at any 90 desired point intermediate its flight, each of said guide members having a platform engaging means whereby said guide members may be carried by said platform for a part of its flight whereby the rollers are maintained 95 in contact with said guide members; fixed guides for each of said guide members; and an adjustable supporting means upon which each of said guide members is slidably mounted embodying a drum, a cable suspended from said drum, and a bumper block secured to one end of said cable. 100

5. A marine elevator embodying an elevator platform suspended at its four corners having a roller operatively mounted on each side thereof; adjustable throwout guide members engageable by said rollers whereby said platform may be moved in a direction at right angles from the vertical at any desired point intermediate its flight; and each of said guide 110 members having a platform engaging means whereby said guide members may be carried by said platform for a part of its flight. 115

In witness whereof I hereunto subscribe my name this 5th day of January, A. D. 1927.

HARRY BARLOW.
